TOYOJIRO INAKI, OF FRESNO, CALIFORNIA, ASSIGNOR OF ONE-HALF TO HOOICHI SUMIDA, OF FRESNO, CALIFORNIA

NASAL IRRIGATOR

Application filed July 11, 1931. Serial No. 550,131.

My invention relates to a nasal irrigator or syringe whereby the nostrils and head can be thoroughly cleansed with water or other liquid desirable to use.

5 My invention has the following objects: The syringe described can be used by a person on himself, or it can be used on another. The liquid to be used as a douche can be flushed alternately into one nostril opening and with- 10 drawn by suction from the other, thus affording a thorough washing of the nasal cavities. It can be taken apart and easily cleaned. It is simple in construction and does not easily get out of working order. Other objects will 15 be hereinafter disclosed.

In the drawings accompanying this specification, Fig. 1 is a view partly in section of the syringe. Figs. 2 and 4 are fractional sectional views of modified forms of the piston 20 rod. Fig. 3 is a cross sectional view along sectional line 3—3 in Fig. 1.

Referring to said drawings, I have provided a tube 5 having a bottom 50 and a top closure 51. I preferably construct the tube 25 of glass so that it can be easily cleaned and the contents readily seen, but other material may be substituted. The closure 51 can be screwed on or otherwise fitted to the top of tube 5 so the fit is liquid tight. Within tube 30 5 is a double acting piston 6. The piston stem 7 is connected at one end to the piston and extends through closure 54 at a sliding fit. A nut 4 holding packing 40 is adapted to make the fit liquid tight. Within piston stem 7 are 35 two conduits, 71 and 72. Conduit 71 extends to the under side of piston 6, and has an outlet 73 thereunder. Conduit 72 terminates at the lower end with an outlet 74 on the upper side of piston 6.

40 It is here noted that while I have shown conduits 71 and 72 as two separate tubes, such conduits can be formed by constructing piston rod 7 hollow with a lateral partition 75 therein.

45 The top ends of conduits 71 and 72 are spaced apart forming a Y, the branches of which are designated 8 and 10. These branches are provided with tips 9 and 11 adapted to fit within the nostrils and adapted 50 to fit tightly on branches 8 and 10. These tips

are preferably made of soft rubber so they can form a liquid tight connection with the nostril without irritation. The spirit of my invention is not confined to the material preferred herein.

55 In applying this device, liquid 12 is placed within the tube, the preference being to fill tube 5 about one-half full, then inserting the piston until it is adjacent to the liquid in the tube, then fill tube 5 on the top of the piston and replace closure 51 on the tube.

60 Insert the tips 9 and 11 in either nostril opening, and then by working the tube 5 up and down on piston 6 the liquid within the tube is forced alternately into one nostril and simultaneously out of the other. When 65 it is desired to let the liquid douche stay in the head for a brief period, it can be done by forcing the liquid through the nostril and then delay working the tube on the piston. When desired to inject liquid into the nostril 70 or out of the nostril without simultaneously ejecting or injecting liquid into the other nostril, but one of the conduits and tips can 75 be used.

Having described my invention I claim:

1. In a nasal syringe the combination of a tube having closures at both ends, a piston within the tube, a piston stem having two conduits laterally within said stem, one having an opening under the piston and the other having an opening above the piston, each of said conduits terminating at the ends outside the tube with a tip adapted to fit the nostril.

80 2. In a nasal syringe the combination of a tube having closures at either end, a double acting piston adapted to fit within the tube, conduits connecting with the chambers within the tube on either side of the piston, each 85 of said conduits terminating at the ends outside the tube with tips adapted to fit within the nostrils.

TOYOJIRO INAKI.
